UNITED STATES PATENT OFFICE.

HENRY B. SAUERMAN AND JOHN A. SAUERMAN, OF CHICAGO, ILLINOIS.

CONVEYER.

941,045.

Specification of Letters Patent. Patented Nov. 23, 1909.

Application filed March 28, 1908. Serial No. 423,944.

To all whom it may concern:

Be it known that we, HENRY B. SAUERMAN and JOHN A. SAUERMAN, citizens of the United States, residing at Chicago, in the 5 county of Cook and State of Illinois, have invented a new and useful Improvement in Conveyers, of which the following is a specification.

Our invention relates, more especially to 10 conveyers for transferring material, such as coal, crushed stone, gravel, sand or other material, from a pile thereof along a horizontal, or substantially horizontal plane, and thence to the place of dumping; and our 15 primary object is to provide a simple construction of conveyer which will be adequate to perform in a highly satisfactory manner the work to be accomplished.

Referring to the accompanying drawing, 20 Figure 1 is a view in side elevation of a portion of conveyer apparatus constructed in accordance with our invention, showing the bucket or scoop in the position it assumes as it travels along the material to be scooped 25 preparatory to scooping up a portion thereof; Fig. 2 is a view like that of Fig. 1, showing the bucket in the position it assumes after it has been operated to fill it; Fig. 3 is a view in sectional elevation of the 30 apparatus illustrated in Fig. 1 with the parts in the position therein illustrated; Fig. 4 is a view similar to that of Fig. 3 showing the parts in the position illustrated in Fig. 2; and Fig. 5, a section taken at the line 5 on Fig. 4 and viewed in the direction of the arrow.

The conveyer-frame is represented at 6 and in the construction shown comprises 40 four upper and lower parallel channel-bars 7 and 8, respectively, forming guide-tracks arranged with their channels 9 and 10 opening toward each other as represented in Fig. 5, and braces 11 connecting the bars together. The channels 10 afford opposed guideways 45 in which travels a conveyer-chain 12 of an endless type comprising links 13 pivotally connected by pins 14 each of which carries a roller 15 at its opposite end, the roller being confined in the guideways 10 to permit 50 the chain to be guided in its movements. Resting in the guideways in the upper bars 7 are rollers 17 in which a shaft 18 is journaled for supporting a depending tripping device in the form of a bail comprising two 55 arms 19 preferably weighted toward their lower ends, and a connecting rod 20. The

shaft 18 is connected to a cable 18^a intermediate its ends, the cable extending around a sheave (not shown) at the end of the conveyer frame to bring the two free ends 60 of the cable 18^a together so that they may be manipulated together to position the trip device at any point along the conveyer-frame.

The bucket or scoop 21 is attached to the 65 conveyer-chain 12 at a point of pivotal connection of one link thereof with another, through the medium of arms 22 journaled at their lower ends to the outer faces of the scoop-sides 23 and 24, as indicated at 25 and 70 26, and at their upper ends on a shaft 27 which takes the place of the usual link-connecting pin at that point.

The bucket employed is preferably of 75 ordinary scoop shape with each side 23 and 24 having straight converging edge-portions 28 and 29 and a rounded portion 30 between which sides the inclosing wall 31, for joining the sides together, extends. The wall 31 thus presents a rounded portion 32 and two 80 converging straight portions 33 and 34, one of which is cut away as represented in the drawings to afford an opening 35 and a penetrating edge 36 for engaging with the material to be scooped in a manner hereinafter 85 explained. The lower ends of the arms 22 are pivoted to the sides 23 and 24 located between the converging portions 28 and 29 so that the arms are preferably pivoted to one 90 side of the center of gravity and extend 90 from such position to the other side of the center of gravity at which they connect with the conveyer-chain, the bucket thus tending to tilt downward at its rounded portion.

The normal position of the scoop, and the 95 position it assumes while traveling over the material to be scooped, is that illustrated in Figs. 1 and 3 in which it rests at its mouth or open portion 35 in substantial contact with the material. Studs 37 are provided 100 on opposed sides of the scoop to engage with the upper edges of the arms 22, and thus arrest the tipping of the bucket at its rounded portion; and hook-shaped lugs 38 located on the rounded portion of the wall 31 105 preferably extend in the positions illustrated in the drawing for engagement with the trip device, as hereinafter described.

In the operation of the conveyer the chain 12, driven by any suitable power device, 110 (not shown), is caused to drag the bucket in the direction indicated by the arrow in Fig.

1, and cause it to engage at its rounded end-
portion with the trip-device, thereby swing-
ing the latter and causing it to engage at its
bar 20 with the lugs 38, whereupon con-
tinued movement of the chain causes the
5 bucket to be turned on the arms 22 to the
position illustrated in Figs. 2 and 4, thus
inverting it. Turning of the bucket, as de-
scribed, causes its penetrating edge 36 to be
10 forced into the material on which the bucket
is traveling and describe an arc through it,
thereby causing material to be scooped up,
whereupon the bucket in its inverted and
filled condition may be moved to the desired
15 point of discharge by further movement of
the chain, and there dumped in any desirable
manner.

The trip device is automatically released
from engagement with the lugs 38 by the
20 turning of the scoop as described, and when
this disengagement has been effected the trip
device swings to its normal depending posi-
tion for again engaging with the bucket
when the latter is again caused to be brought
25 into engagement with the trip device.

It is manifest that if desired a plurality
of buckets 21 may be connected with the
conveyer-chain 12, as by duplication thereof,
and thus as the buckets successively engage
30 the trip-device they will be caused to scoop
up material as described of the bucket 21.

While we have illustrated and described
our invention as embodied in the form of
conveyer which moves in a horizontal path,
35 we do not wish to be understood as limiting
our invention to its use in so-called hori-
zontal conveyers, as it may be embodied in
a conveyer operating in an inclined direc-
tion, or one in which the bucket engages a
40 pile of material having a substantially flat
or inclined upper surface, and after filling is
raised to the point of dumping, a type of
conveyer operating in this last referred-to
manner being that known as the vertical
45 type.

What we claim as new and desire to se-
cure by Letters Patent, is—

1. The combination of a traveling flexi-
ble carrier, a support upon the carrier, a
50 scoop pivotally mounted on said support
and movable bodily toward and away from
said carrier, and a swinging trip-device ex-
tending into the path of movement of the
scoop and constructed and arranged to turn
55 the latter to digging, loading and carrying
position.

2. The combination of a traveling bucket,
a support, and a depending swingingly-
mounted trip-device pivoted to said support
60 and constructed and arranged to engage
with the bucket and turn it to digging, load-
ing and carrying position while in engage-
ment with the material being operated on,
for the purpose set forth.

65 3. The combination of a traveling bucket,

a support, and a depending swingingly-
mounted trip-device pivoted to the support
and having a cross-bar at which it is adapt-
ed to engage with the bucket to turn it to
digging, loading and carrying position while
70 in engagement with the material being op-
erated on, for the purpose set forth.

4. The combination with a traveling flexi-
ble carrier, of a support upon the carrier, a
scoop pivotally mounted on the support and
movable bodily toward and away from the
carrier, a trip-engaging device on the scoop,
75 and a swinging scoop-engaging-and-turning
stop in the path of the scoop, for the purpose
set forth.

5. The combination with a traveling flexi-
ble carrier, of a support upon the carrier, a
scoop pivotally mounted on the support and
movable bodily toward and away from the
carrier, and a scoop-engaging-and-turning
85 stop in the path of the scoop and constructed
and arranged to be adjusted into different
positions relative to the material to be
scooped, for the purpose set forth.

6. The combination with a conveyer-
frame and a traveling flexible carrier sup-
ported thereon, of a support upon the car-
rier, a scoop pivotally mounted on the sup-
port and movable bodily toward and away
95 from the carrier, and a scoop-engaging-and-
turning stop adjustable on said frame and
extending into the path of the scoop, for the
purpose set forth.

7. The combination of a suitably-sup-
ported traveling-support, arms carried by
the support, a bucket of scoop shape piv-
oted to said arms to one side of the center
of gravity of the bucket, means for arrest-
ing the tilting of the bucket, and means con-
structed and arranged to engage with the
105 bucket and turn it to digging, loading and
carrying position while in engagement with
the material being operated on, for the pur-
pose set forth.

8. The combination of a traveling carrier,
110 a support on the carrier, a bucket having
an open side pivotally connected with said
support and movable bodily toward and
away from the carrier, the connection be-
tween said support and bucket being at one
115 side of the vertical center line of gravity of
the bucket when the open side thereof is in
the horizontal plane, and means in the path
of movement of the bucket for turning the
latter upon the support, for the purpose set
120 forth.

9. The combination of a traveling carrier,
a support on the carrier formed with a plu-
rality of depending members, a bucket hav-
ing an open side pivotally connected with
125 said depending members and movable bodily
toward and away from the carrier, the con-
nection between said members and bucket
being at one side of the vertical center line
of gravity of the bucket when the open side
130

thereof is in the horizontal plane, and means in the path of movement of the bucket for turning the latter upon said depending members, for the purpose set forth.

- 5 10. The combination of a traveling carrier, a swinging support on the carrier, a bucket having an open side pivotally connected with said support and movable bodily toward and away from the carrier, the connection between said support and bucket being at one side of the vertical center line of gravity of the bucket when the open side thereof is in the horizontal plane, and means in the path of movement of the bucket for turning the latter upon said support, for the purpose set forth.
- 10 11. The combination of a traveling carrier, a support on the carrier formed of a plurality of arms pivotally connected thereto, a bucket having an open side pivotally connected with said arms and movable bodily toward and away from the carrier, the connection between said arms and bucket being at one side of the vertical center line of gravity of the bucket when the open side thereof is in the horizontal plane, and means in the path of movement of the bucket for turning the latter upon its arms, for the purpose set forth.
- 15 12. The combination of a traveling carrier, a support on the carrier, a bucket having an open side pivotally connected with said support and movable bodily toward and away from the carrier, the connection between said support and bucket being at one side of the vertical center line of gravity of the bucket when the open side thereof is in the horizontal plane, and means in the path of movement of the bucket for turning the latter upon said support, for the purpose set forth.
- 20 13. The combination of a traveling carrier, a support on the carrier, a bucket having an open side pivotally connected with said support and movable bodily toward and away from the carrier, the connection between said support and bucket being at one side of the vertical center line of gravity of the bucket when the open side thereof is in the horizontal plane, a trip-engaging device on the bucket located on the opposite side of the vertical central line of gravity, and means engaging with said trip-engaging device for turning the bucket, for the purpose set forth.
- 25 14. The combination of a conveyer-frame, a traveling flexible carrier supported on the frame, a support upon the carrier, a bucket having an open side pivotally connected with said support and movable bodily toward and away from the carrier, the connection between said support and bucket being at one side of the center line of gravity of the bucket when the open side thereof is in the horizontal plane, a trip-engaging device on the bucket, and means on said frame for engaging said trip-engaging device, for the purpose set forth.
